UNITED STATES PATENT OFFICE.

WILLIS B. KINNEAR, OF YOUNGSVILLE, PENNSYLVANIA.

STORM WINDOW SCREEN.

Application filed July 31, 1925. Serial No. 47,346.

The present invention appertains to a storm window screen, and has for its principal object to provide a structure which may be easily and quickly engaged in a window frame, and allowed to remain therein all the year around.

Another important object of the invention is to provide a screen of this nature having a shutter structure incorporated therein whereby the panels thereof may be left open during rain, at such an angle as to prevent the rain from beating in through the window.

Another important object of the invention is to provide a device of this nature which is operable from the inside only, and thus will function to prevent persons from having access through the window for entrance purposes.

20 A still further very important object of the invention is to provide a window screen of this nature which is exceedingly simple in its construction, strong, durable, inexpensive to manufacture, easy to manipulate, efficient and reliable, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

35 Figure 1 is an outside elevation of the device,

Figure 2 is an inside elevation thereof,

Figure 3 is a vertical section therethrough taken substantially on the line 3—3 of Figure 2,

40 Figure 4 is an edge view of one end of the device showing a portion in section,

Figure 5 is a section through the portion of the screen proper, and

45 Figure 6 is a detail perspective view of one of the shutter panels.

Referring to the drawing in detail it will be seen that 5 designates generally the frame which has one end reduced as at 6 for the reception of the reduced portion 7 of an adjustable extension 8. The adjustable extension 8 has its reduced portion 7 provided with slots 9 for receiving bolts 10. Nuts 11 are associated with the bolts 10, and are preferably of the wing type. Slots 12

are provided in the reduced end 6 in registry with the slots 9, and receive the bolts 10. The wing nuts 11 are adapted to be disposed in countersunk recesses 13 in the end 6. It will thus be seen that the widths of the frame may be adjusted to fit the window frame snugly, and when these nuts 11 are securely tightened, the frame is prevented from accidental removal, and also from unauthorized removal from the outside. The 65 frame in its front portion has hingedly mounted therein a plurality of panels 14 forming a shutter structure. Each panel 14 is provided at its lower edge with pintles 15 extending beyond its ends for rotatable engagement in the sides or ends of the frame. The lower and upper edges of the panels are reduced as is indicated at 16 and 17 respectively, so that the shutters may be placed in overlapping coplanar association as shown 70 in Figure 3, at which time, of course, the shutter structure is closed. An eye 18 is fixed in one of the free corners of each panel, and a link 19 is pivotally engaged therewith. Apertured lugs 20 are provided at the top 75 and bottom of the frame, and slidably receive the ends of a rod 21. A spring 22 has its upper end attached to the upper portion of the frame, and its lower end attached to the upper end of the rod 21, and normally holds this rod 21 lifted so that the links 19 80 which are pivoted to the rod hold the panels 14 of the shutter structure closed. An opening 24 is provided in one end of the frame and has ratchet teeth 25 formed along one 85 edge thereof. An arm 26 projects from an intermediate portion of the rod 21 and is engageable with the ratchet teeth 25 so that the rod 21 may be held in different adjusted positions for holding the panel 14 in different 90 adjusted open positions.

A sheet of foraminous material indicated at 28 has a channel frame 29 disposed thereabout. This frame 29 is receivable in a seat 30 formed in the frame so as to be flush 100 with the adjacent face thereof. The lower portion of the frame 29 is held in place by suitable lugs 32 while the upper side thereof is held in place by a screw 33 or in any other suitable manner.

105 From the above description it will be seen that I have devised a very efficient and reliable structure which may be placed in a window frame, and controlled from the inside of the house, to prevent the entrance 110

of unauthorized persons, and also to prevent the entrance of rain, and of course the device may be fully closed to keep out cold weather when so desired.

- 5 It will further be seen that the panels of the shutters are very easily adjusted to the desired angle when ventilation is needed. The present embodiment of the invention has been disclosed in detail since in actual 10 practice it attains the features of advantage enumerated as desirable in the statement of the invention and the above description. It will be apparent, however, that numerous changes in the details of construction, and 15 in the combination and arrangement of parts may be resorted to without departing from the spirit or scope of the invention as hereinafter claimed or sacrificing any of its advantages.
- 20 Having thus described the invention, what I claim as new and desire to secure by Letters Patent is:—

In a structure of the class described, a frame, a plurality of shutter panels hingedly mounted in the frame, links pivotally engaged with the panels, a rod slidable in the frame, said links pivotally engaged with said rod, a spring fixed to said rod and said frame to maintain the shutters normally closed, said frame being provided with an opening, an arm fixed to the rod and extending through the opening, and ratchet teeth provided on one side of the opening with which the arm is engageable, said spring normally holding said arm in engagement with the ratchet teeth through the intermediacy of said rod whereby the shutters may be maintained in different adjusted open positions.

In testimony whereof I affix my signature.

WILLIS B. KINNEAR.
